BIT BREAKER

Wesley P. Kincaid, Oklahoma City, Okla., assignor to Reed Roller Bit Company, Houston, Tex., a corporation of Texas

Application October 12, 1939, Serial No. 299,057

4 Claims. (Cl. 255—1)

This invention relates to bit breakers, for use in rotary oil well drilling in removing rotary bits from drill collars.

In this art, when a drill bit is pulled out of the hole to be changed, some means must be provided for holding the bit while the threaded coupling or drill collar which attaches it to the drill string is broken out and unscrewed. For this purpose an auxiliary bit-holding device is utilized which fits in the rotary table and supports the bit, at the same time holding it from rotation with respect to the table. Heretofore such devices have taken the form of break out plates so designed that they received and engaged the bits at about the level of their cutters or cutting portions.

It is an object of this invention to provide a break out plate which will engage the shank of a bit above its cutting portion and thus avoid any injury to the cutting portions of the bits.

Other objects and features will become evident from the following disclosure, taken in connection with the accompanying drawing, in which—

Fig. 1 is a plan view of the bit breaker;

Fig. 2 is a side elevation of the bit breaker in position in the top of a rotary table; and

Fig. 3 is a side elevation of the bit breaker.

Referring to the drawing in detail, plates 10, 10a are identical in shape, and may be cast from the same pattern. They are of such a shape that they snugly fit into the top of the rotary table, in the square recess which carries the drive bushing, as shown in Fig. 2. The plates 10 are formed with an aperture 11 shaped to receive and hold a drill bit, at a point spaced from its end. Handles 12, 12a are welded to the top of the halves, so the device may be conveniently lifted and handled for attachment and detachment.

Below the plate halves there are, formed integral therewith, inwardly disposed L-shaped supporting members 13, 13a, joined by a hinge 14 of conventional construction. Where the two halves meet (see Fig. 1) there are also formed oppositely disposed lugs and coacting apertures 15 which prevent any sideways stress on the hinge when the plates are being closed on the bit.

In operation, the bit is pulled out of the hole and raised to a point about a foot above the rotary table. Two men then grasp the bit breaker by the handles 12 and 12a, holding it open, and slip it on the bit past the end thereof until the end engages the supporting members 13 and

13a, and the edges of the aperture are closed on the reduced portion of the bit. They can then hold the bit breaker in position while the bit is lowered until the plate 10, 10a fits in the recess on the top of the rotary table. (It will be obvious that the weight of the bit on the supporting members 13, 13a causes the bit to be gripped tighter by the edges of the aperture 11.) The drill collar may then be broken out and the bit removed from the bit breaker.

Although a preferred embodiment of my invention is herein disclosed, I do not wish to be limited thereto, but only to the scope of the appended claims.

I claim:

1. In a bit breaker, a pair of opposing plates positioned so that their edges will contact and hold a drill bit therebetween, and supporting means hinging said plates together so that the weight of a bit on the supporting means will cause the plates to press on the bit.

2. In a bit breaker, a pair of opposing plates positioned normally in the same plane so that their edges will contact and hold a drill bit therebetween, depending L-shaped supporting members made integral with said plates, said members hinged together below said plates in position to support a bit so that the weight of the bit will cause the plates to press on the bit.

3. In a bit breaker, two opposing plates positioned normally in a horizontal plane, a bit engaging aperture formed in the opposing edges of said plates, depending L-shaped supporting members made integral with said plates, said members hinged together below said aperture in position to support a bit so that the weight of the bit will cause the edges of the aperture to press on the bit.

4. In a bit breaker, two plates together forming substantially a square separated on a diagonal, a bit engaging aperture formed out of both plates symmetrical on the dividing line between the two plates, lugs and coacting apertures in the adjoining edges of the two plates, a handle on each plate, a depending L-shaped supporting member made integral with each plate, said members hinged together so that the weight of the bit on the supporting members causes the edges of the aperture to press against the side of the bit.

WESLEY P. KINCAID.
